Primary Examiner — Derrick Holland*Assistant Examiner* — Jennifer O King(74) *Attorney, Agent, or Firm* — Cargill & Associates, PLLC; Lynn E. Cargill(57) **CLAIM**

The ornamental design for an air travel carrier bag, as shown.

DESCRIPTION

FIG. 1 is a front elevational view of an air travel carrier bag showing my new design;

FIG. 2 is a right side elevational view thereof;

FIG. 3 is a rear elevational view thereof;

FIG. 4 is a left side elevational view thereof;

FIG. 5 is a top plan view thereof; and,

FIG. 6 is a bottom plan view thereof.

The dash-dot broken line showing of a window represents unclaimed subject matter and forms no part of the claimed design. The evenly spaced broken lines represent stitching, which forms no part of the claimed design.
